(57) **CLAIM**

The ornamental design for a sconce, as shown and described.

DESCRIPTION

FIG. 1 is a front perspective view of a sconce; FIG. 2 is a front elevational view of the sconce; FIG. 3 is a rear elevational view of the sconce; FIG. 4 is a left side elevational view of the sconce; FIG. 5 is a right side elevational view of the sconce; FIG. 6 is a top plan view of the sconce; FIG. 7 is a bottom plan view of the sconce; and, FIG. 8 is a bottom perspective view of the sconce. The broken line portions of the drawings are included to show portions of the article that form no part of the claimed design and represent environmental structure only.

1 Claim, 8 Drawing Sheets
